TOY PISTOL

William S. Wells, Palo Alto, Calif., and Richard I. Daniel, Rogers, Ark., assignors to Daisy Manufacturing Company, Rogers, Ark., a corporation of Nevada
Filed Mar. 10, 1961, Ser. No. 94,811
9 Claims. (Cl. 124—27)

This invention relates to toy pistols and more particularly to toy pistols having spring mechanisms for propelling pellets or the like.

Today, toy pistols are manufactured as highly realistic models of full scale weapons. In many cases a substantial replica cannot be manufactured since most mechanisms for firing pellets or the like interfere with the design of an exterior housing which is equivalent to the housing of a full scale weapon.

An object of this invention therefore is to provide an improved toy pistol which has the characteristic shape and size of a real weapon and a spring-propelling mechanism which is highly effective in propelling pellets such as conventional BB's or the like.

A further object of the invention is to provide an improved toy pistol having a realistic hammer and trigger mechanism which positively cocks a catapult-type spring in a firing position with respect to a pellet or the like.

A further object of the invention is to provide an improved toy pistol having a realistic hammer and trigger mechanism which releases a catapult-type spring to fire a pellet or the like from the pistol at relatively high velocities while maintaining a low trigger force.

A further object of the invention is to provide an improved toy pistol having a catapult-type spring-actuated propelling mechanism which is cocked into a firing position by a realistic appearing hammer mechanism and a jam-proof feed mechanism for positioning pellets or the like with respect to the propelling mechanism.

A still further object of the invention is to provide an improved toy pistol having a catapult-type spring-actuated propelling mechanism in combination with a realistic hammer and trigger mechanism which requires a substantial positive manual force to move the hammer to load the catapult-type spring and requires only a small manual force to move the trigger to release the hammer and the catapult-type spring.

Other objects and features of the novelty of the invention will be specifically pointed out or otherwise become apparent when referring, for a better understanding of the invention, to the following description taken in conjunction with the accompanying drawings, wherein:

FIGURE 1 is a side view partially in section and partially in elevation, of a pistol constructed in accordance with the principles of the invention with the pistol's operative mechanism in a fired position;

FIGURE 2 is a view similar to FIGURE 1 with the pistol's operative mechanism in a first cocked position;

FIGURE 3 is a view similar to FIGURE 1 with the pistol's operative mechanism in a loading position;

FIGURE 4 is a view similar to FIGURE 1 with the pistol's operative mechanism in a "ready-to-fire" position;

FIGURE 5 is an enlarged fragmentary sectional view taken substantially along the line 5—5 of FIGURE 1 looking in the direction of the arrows;

FIGURE 6 is an enlarged fragmentary sectional view taken substantially along the line 6—6 of FIGURE 1 looking in the direction of the arrows;

FIGURE 7 is an enlarged fragmentary sectional view taken substantially along the line 7—7 of FIGURE 1 looking in the direction of the arrows;

FIGURE 8 is an enlarged fragmentary sectional view taken substantially along the line 8—8 of FIGURE 2 looking in the direction of the arrows;

2

FIGURE 9 is an elevational view of a shot follower for feeding pellets or shot into the pistol's operative mechanism;

FIGURE 10 is an enlarged horizontal section taken along the line 10—10 of FIGURE 1 looking in the direction of the arrows;

FIGURE 11 is an enlarged fragmentary sectional view taken substantially along the line 11—11 of FIGURE 3 looking in the direction of the arrows;

FIGURE 12 is an enlarged fragmentary sectional view taken substantially along the line 12—12 of FIGURE 4 looking in the direction of the arrows; and

FIGURE 13 is an enlarged fragmentary sectional view taken substantially along the line 13—13 of FIGURE 4 looking in the direction of the arrows.

Referring to the drawings, FIGURES 1—13 illustrate one embodiment of the invention. Reference numeral 20 generally designates a pistol having an exterior housing which is a substantial replica of a full scale weapon of

20 the type having a hammer-actuated firing mechanism and a cylinder of several chambers so arranged as to revolve on an axis, and be discharged in succession by the hammer-actuated firing mechanism. The toy pistol 20 includes an outer housing 22 which consists of interlocking castings or the like which surround the operative mechanism of the present invention and includes a barrel or front portion generally designated 24, and a stock or rear portion generally designated 26.

A pivot pin 28 mounted in the stock 26 pivotally carries 30 a trigger 30 which extends through an aperture 32 formed in the housing 22. The housing 22 has an integral trigger guard 34 depending from either side of the aperture 32 and surrounding the trigger 30 for preventing accidental firing of the pistol.

A pivot pin 36 mounted in the stock 26 pivotally carries 35 a hammer, generally designated 38, which extends through an aperture 40 formed in the housing 22. The hammer 38 and the trigger 30 are full scale replicas of similar elements found in a revolver having a cylinder of several chambers so arranged as to revolve on an axis, and be discharged in succession by a hammer-actuated firing mechanism.

The front portion 24 of the housing 22 has a sub-barrel 42 integrally formed therewith. An aperture 44 formed therein admits pellets or the like into the interior 45 of the sub-barrel 42.

A follower mechanism for feeding pellets from the sub-barrel 42 to the firing mechanism includes a compression spring 46 disposed in one end of the sub-barrel 42 in axial abutment with a shot follower 48 which preferably comprises an elongated finger of polyethylene or similar natural or synthetic resilient materials. The shot follower 48, as best shown in FIGURE 10, has a groove 50 formed in one end thereof for a follower tab 52 which 50 extends outwardly from the sub-barrel 42 through a slot 54 formed therein. A small diameter protuberance 56 extending from the same end fits within the compression spring 46.

The sub-barrel 42 communicates with a feed tube 60 60 which bends between the sub-barrel 42 and the firing mechanism of the pistol for feeding pellets thereto. Therefore, the shot follower 48 has a plurality of grooves 58 formed therein to impart a substantial flexibility to the shot follower 48 which extends into the feed tube 60, assuming the shape thereof.

To load the pistol, the follower tab 52 is moved toward the front end of the sub-barrel 42 compressing the spring 46 and moving the shot follower 48 to open the aperture 44. BB's or the like inserted in the aperture 44 roll upwardly into the feed tube 60. Release of the follower tab 52 causes the compression spring 46 to hold the shot follower 48 in axial engagement with the pellets within the feed tube 60.

The front housing portion 24 has an internal bracket 62 integrally formed therein which carries a longitudinally extending inner barrel 64 through which pellets are fired by the firing mechanism of the pistol 20 through an aperture 65 formed in the end of the housing 22. The inner barrel 64 extends into a rear chamber housing generally designated 66. The rearward portion of the housing 22 has brackets 68, 70 integrally formed therewith which carry the chamber housing 66.

The chamber housing 66 communicates with the feed tube 60 through an aperture 72 in the wall of the housing 66. A compression spring 74 in the rear portion of the housing 66 axially abuts against a shot control button 76 slidingly mounted in housing 66. The spring 74 holds the button 76 against a stop spring 78 which extends into a bore 80 in the chamber housing 66 through an aperture 82 formed in the wall of the chamber housing 66.

The chamber housing 66 has an aperture 84 extending throughout its longitudinal length that receives one end of a main firing spring 86 which extends into the bore 80 for catapulting or firing a pellet disposed in front of the spring 86 in a manner to be described.

The firing spring 86 encircles a boss 88 formed in the housing 22 below the chamber housing 66. The other end of the spring 86 bears against an abutment 90 integrally formed in the housing 22. The housing 22 also has a pin 92 integrally formed therewith which carries a bumper 94 preferably formed of rubber or a similar natural or synthetic resilient material. The firing spring 86 engages the bumper 94 at the end of its firing path to reduce impact wearing of the housing 66 and the spring 86.

The firing mechanism of the pistol 20 includes the trigger 30, the hammer 38 and a sear or latch generally designated 96. A draw link 98 mounted on the hammer 38 and guided by a rod 99 extending transversely in the housing 22 engages the firing spring 86 for pivoting it around the boss 88 as the hammer 38 pivots around the pivot pin 36.

Brackets 100 and 102 are integrally formed in the stock portion 26 of the pistol 20 and carry a pivot pin 104 which pivotally supports the sear 96 with respect to the firing spring 86 and the hammer 38. An arm 105 formed integrally with the housing 22 holds the pin 104 in the brackets 100, 102. A compression spring 106 mounted between the housing 22 and a front leg portion 108 of the sear 96 holds the sear 96 against the spring 86 when it is in subsequently described "pre-draw" or "ready-to-fire" positions. A stop arm 110 extends laterally from the housing 22 to prevent the leg 108 from blocking the rearward or cocking movement of the spring 86. The spring 86 contacts a forward cam portion 112 on the sear 96 during its rearward movement to move the sear 96 to one side. Once the spring 86 passes over the cam portion 112 the sear 96 is held against the stop arm 110 by the compression spring 106 and a face portion 114 thereon releasably holds the firing spring 86 in its "ready-to-fire" position.

The sear 96 has a rear leg portion 116 having a groove 118 which follows a cam projection 120 formed on the hammer 38 to release the main spring 86. The trigger 30 has a head portion 122 which contacts a shoulder 124 on the hammer 38 when the hammer 38 is pivoted about the pin 36 as the spring 86 is moved into a cocked position.

A coil spring 126 fastened at one end to a pin 128 formed integrally with a housing 22 and at the other end to the hammer 38 returns the hammer 38 to the fired position. A resilient bent spring 130 connects the trigger 30 to a pin 132 formed integrally with the housing 22 for holding the trigger 30 against the hammer 38.

Toy pistols constructed in accordance with the principles of the present invention are especially suited to "quick draws" by children for reasons to be described.

FIGURES 1 and 5-7 illustrate a fired position with the firing spring 86 disposed in the front portion of the firing chamber 66. In order to reduce the time to cock the pistol 20 during a "fast draw" while maintaining the gun in an unloaded or safety position, the hammer 38 is pivoted rearwardly from the fired position until head portion 122 of the trigger 30 is in engagement with the shoulder 124 on the hammer 38. This position is illustrated in FIGURES 2 and 8. Pellets or BB's 134 disposed in the feed tube 60 are blocked from entering the rear chamber bore 80 since the shot control button 76 and the spring 86 block the aperture 72. Furthermore, a substantial pull must be exerted on the trigger 30 to release the hammer 38 since the full force of the spring 86 is holding the hammer 38 against the trigger 30. However, it is obvious that a revolver having the main spring positioned in such a safety or "pre-draw" position can be quickly cocked to load the revolver and to place the revolver in a "ready-to-fire" position.

To load a pellet or BB 134 into the bore 80, the hammer 38 is pivoted to the extreme rearward position to cause the spring 86 to move the button 76 away from the aperture 72 so that a BB 134 will be pushed by the shot follower 48 into the bore 80. The diameter of the bore 80 is reduced a substantial amount at the point where the aperture 72 intersects. Therefore, after a pellet or BB 134 moves into the bore 80, the hammer 38 and spring 86 move forwardly until the spring 86 is latched by the notch 114 on the sear 96. The slight forward movement of the spring 86 pushes the pellet or BB 134 into a portion of the bore 80 having a full diameter at a point near but spaced from the aperture 72. Thus, when the trigger 30 is released to fire the pistol 20, the pellet or BB 134 will be completely encased by the chamber housing 66 at a point where the diameter of bore 80 is full sized. The complete encasement and full diameter prevent a pellet or BB 134 from jamming within the chamber housing 66. The loading step and the positioning of the pellet or BB 134 in a firing position are best illustrated in FIGURES 3 and 11.

When the revolver is in a "ready-to-fire" position, the sear or latch assembly 96 engages the main spring 86 and the front portion of the draw link 98 is positioned forwardly of the firing spring 86. The pistol 20 is designed to fire from this position, because it gives the draw link 98 a head start on the main spring or firing spring 86. It also releases the main spring force on the draw link 98 which in turn releases the force on the trigger 30, hammer 38, and reduces the trigger force required to fire the pistol 20. The reduced trigger force obviously reduces the time that it takes to fire the revolver at a target during a "quick-draw."

When the trigger 30 is moved rearwardly, the head portion 122 pivots away from the shoulder 124 on the hammer 38 causing the hammer 38 to pivot forwardly. The forward motion of the hammer 38 causes the cam projection 120 to strike the surface 118 on the rear leg portion 116, causing the face portion 114 to pivot away from and release the spring 86. The released spring 86 acts as a catapult, moving forwardly about the pivot pin 88 against the encased BB 134 for directing it at a relatively high velocity into the barrel 64 which directs the pellet or BB in a preselected direction. At the end of the firing path the spring 86 will strike the resilient bumper 94.

The illustrated embodiment of a toy pistol constructed in accordance with the concepts of the present invention has been found especially suited for practicing "quick draws." The pistol retains the characteristic shape and size of a full scale weapon and has an effective spring catapult firing mechanism for firing BB's or pellets at a high velocity from the pistol. Moreover, a toy pistol in accordance with the present invention, has a quick trigger action since the trigger force is reduced to a low level, even though the spring catapult firing action is the result

of a large spring force. Furthermore, the anti-jamming features of the gun reduce the chance of a pellet being jammed in the spring catapult firing system.

While it will be apparent that the embodiment of the invention herein disclosed is well calculated to fulfill the objects of the invention, it will be appreciated that the invention is susceptible to modification, variations and change without departing from the proper scope or fair meaning of the subjoined claims.

What is claimed is:

1. A toy pistol comprising a housing, a chamber within said housing, a spring pivotally mounted on said housing, a portion of said spring extending into said chamber for propelling pellets disposed within said chamber, hammer means pivotally supported on said housing, trigger means pivotally supported on said housing releasably engaging said hammer means for locking said hammer means against pivotal movement in one direction, link means connected to said hammer means and operatively connected to said spring for moving said spring portion rearwardly in said chamber when said hammer means is pivoted in a direction opposite to said one direction, latch means releasably engaging said spring to prevent movement of said spring in said one direction and to operatively disengage said spring from said hammer means to reduce the trigger force required to release said hammer means when said hammer means is in a predetermined position, and means operatively connecting said hammer means and said latch means for releasing said spring against a pellet in said chamber.

2. A toy pistol comprising a housing, a chamber within said housing, a spring pivotally mounted on said housing, a portion of said spring extending into said chamber for propelling pellets disposed within said chamber, hammer means pivotally supported on said housing, trigger means pivotally supported on said housing releasably engaging said hammer means for locking said hammer means against pivotal movement in one direction, link means connected to said hammer means and operatively connected to said spring for moving said spring portion rearwardly in said chamber when said hammer means is pivoted in a direction opposite to said one direction, latch means releasably engaging said spring to prevent movement of said spring in said one direction and to operatively disengage said spring from said hammer means to reduce the trigger force required to release said hammer means when said hammer means is in a predetermined position, and said hammer means having a cam portion engaging said latch means for releasing said spring when said trigger means is pivoted to fire the pistol.

3. A toy pistol comprising a housing, a chamber within said housing, a spring pivotally mounted on said housing, a portion of said spring extending into said chamber for propelling pellets disposed within said chamber, hammer means pivotally supported on said housing operatively connected to said spring for moving said spring with respect to said chamber, trigger means pivotally supported on said housing releasably engaging said hammer means for locking said hammer means against pivotal movement in one direction, a sear having a front leg and a rear leg, said front leg having a face portion restraining said spring when said hammer means is in a predetermined position, and said hammer means having a cam portion engageable with said rear leg for releasing said spring when said trigger means is pivoted to fire the pistol.

4. A toy pistol comprising a housing, a chamber within said housing, a spring pivotally mounted on said housing, a portion of said spring extending into said chamber for propelling pellets disposed within said chamber, a hammer pivotally supported on said housing, trigger means pivotally supported on said housing releasably engaging said hammer for locking said spring in a partially cocked position, a draw link connected to said hammer and operatively connected to said spring for moving said spring

rearwardly in said chamber when said hammer is pivoted in one direction, latch means releasably engaging said spring to prevent movement of said spring in a direction opposite to said one direction and to operatively disengage said spring from said hammer to reduce the trigger force required to release said hammer when said hammer is in a predetermined position, and surfaces on said hammer and said trigger means for positioning said hammer at a predetermined point to locate, the free end of said spring at a point spaced from the forward end of said draw link when said latch means releasably engages said spring to prevent interference between said draw link and said spring when said spring is released and means including said trigger means, said hammer and said latch means for releasing said spring against a pellet in said chamber.

5. A toy pistol comprising a housing, a first barrel having a chamber portion, means defining an aperture in said chamber portion, a second barrel depending from said first barrel communicating with said aperture, means in said second barrel feeding pellets through said aperture into said chamber portion, a spring pivotally mounted on said housing, a free end of said spring extending into said chamber portion for propelling pellets out of said first barrel, feed control means including a button in said chamber portion operatively coupled to said spring for selectively opening and closing said aperture, a hammer pivotally supported on said housing, trigger means pivotally supported on said housing releasably engaging said hammer for locking said spring in a partially cocked position, a draw link connected to said hammer and operatively connected to said spring for moving said free end of said spring rearwardly in said chamber when said hammer is pivoted in one direction, latch means releasably engaging said spring to prevent movement of said spring in a direction opposite to said one direction and to operatively disengage said spring from said hammer to reduce the trigger force required to release said hammer, surfaces on said hammer and said trigger means for positioning said hammer to locate said free end of said spring at a point spaced from the forward end of said draw link when said latch means releasably engages said spring to prevent interference between said draw link and said spring when said spring is released, and said hammer having a cam portion engaging said latch means for releasing said spring when said trigger means is pivoted to fire the pistol.

6. A toy pistol comprising a housing, a first barrel having a chamber portion, means defining an aperture in said chamber portion, a second barrel depending from said first barrel communicating with said aperture, means in said second barrel for feeding pellets into said chamber portion, a firing spring pivotally mounted on said housing, a free end portion of said firing spring extending into said chamber portion for propelling pellets out of said first barrel, a pellet stop spring mounted in said chamber portion between the outlet of said barrel and said aperture, a feed control button biased against said firing spring movable into a first position blocking said aperture and a second position opening said aperture, a hammer pivotally supported on said housing, a draw link mounted on said hammer means operatively connected to said firing spring for moving said main spring and said feed control button away from said aperture to feed a pellet between said firing spring and said stop spring, trigger means pivotally supported on said housing releasably engaging said hammer for locking said spring in a partially cocked position, latch means releasably engaging said spring when said hammer is in a predetermined position to operatively disengage said spring from said draw link to reduce the trigger force required to release said hammer, surfaces on said hammer and said trigger means for positioning said hammer to locate said free end of said spring at a point spaced from the forward end of said draw link to prevent said draw link

from interfering with said spring when said spring is released, and said hammer having a cam portion engaging said latch means for releasing said spring when said trigger means is pivoted to fire the pistol.

7. A toy pistol comprising a housing, a chamber within said housing, means defining a first aperture rearwardly of said chamber, a partially curved feed tube within said housing having one end communicating with said first aperture, means defining a second aperture between the ends of said feed tube for loading pellets into said feed tube, an elongated flexible strip slidably mounted in said feed tube, spring means in said feed tube for urging said elongated flexible strip in a direction to block said second aperture and to force pellets in said feed tube through said first aperture in said chamber, means for blocking the entrance of pellets into said chamber, a spring pivotally mounted within said housing, a portion of said spring extending into said chamber for propelling pellets disposed within said chamber, hammer means pivotally supported on said housing, trigger means pivotally supported on said housing releasably engaging said hammer means for locking said hammer means against pivotal movement in one direction, and link means connected to said hammer means and operatively connected to said spring for moving said spring rearwardly in said chamber when said hammer means is pivoted in a direction opposite to said one direction to coat with said means for blocking the entrance of pellets into said chamber to permit the passage of a pellet through said first aperture into said chamber.

8. A toy pistol comprising a housing, a chamber within said housing, means defining a first aperture rearwardly of said chamber, a partially curved feed tube within said housing having one end communicating with said aperture, means defining a second aperture between the ends of said feed tube for loading pellets into said feed tube, an elongated strip of resilient material slidably mounted in said feed tube having a plurality of transverse grooves for increased flexibility, spring means in said feed tube for urging said elongated strip in a direction to block said second aperture and to force pellets in said feed tube through said first aperture in said chamber, means for blocking the entrance of pellets into said chamber, a spring pivotally mounted within said housing, a portion of said spring extending into said chamber for propelling

pellets disposed within said chamber, hammer means pivotally supported on said housing, trigger means pivotally supported on said housing releasably engaging said hammer means for locking said hammer means against pivotal movement in one direction, and link means connected to said hammer means and operatively connected to said spring for moving said spring rearwardly in said chamber when said hammer means is pivoted in a direction opposite to said one direction to coat with said means for blocking the entrance of pellets into said chamber to permit the passage of a pellet through said first aperture into said chamber.

9. A toy pistol comprising a housing, a chamber within said housing, means defining an aperture rearwardly of said chamber, spring means mounted in said chamber rearwardly of said aperture, a button slidably mounted in said chamber forwardly of said spring means and urged by said spring means into a location at which said button completely blocks said aperture, an elongated spring arm pivotally mounted within said housing, a free end portion of said spring arm extending into said chamber for propelling pellets disposed within said chamber, hammer means pivotally supported on said housing, trigger means pivotally supported on said housing releasably engaging said hammer means for locking said hammer means against pivotal movement in one direction, link means connected to said hammer means and operatively connected to said spring arm for moving said free end of said spring arm rearwardly in said chamber to engage said button and move it rearwardly of said aperture to permit the insertion of a pellet through said aperture into said chamber forwardly of said spring arm, and surfaces on said hammer means and said trigger means locating said spring arm forwardly of said aperture following the insertion of a pellet into said chamber to prevent a pellet from jamming in said chamber.
